UNITED STATES PATENT OFFICE.

WILLIAM S. HADAWAY, JR., OF NEW ROCHELLE, NEW YORK.

ELECTRIC HEATER.

1,155,483.

Specification of Letters Patent.

Patented Oct. 5, 1915.

Application filed May 20, 1914. Serial No. 339,672.

To all whom it may concern:

Be it known that I, WILLIAM S. HADAWAY, Jr., a citizen of the United States of America, and a resident of New Rochelle, 5 Westchester county, and State of New York, have invented certain new and useful Improvements in Electric Heaters, being a continuation of my application Serial No. 823,372 filed March 9, 1914, of which the 10 following is a specification, reference being had to the accompanying drawings, forming a part thereof.

My invention relates to electric heaters and has for one of its objects to provide a 15 simple and efficient device of this character that shall possess advantages usually pertaining to widely different heaters and not hitherto attainable in a single heater.

Another object is to provide a heater unit 20 that shall comprise a relatively massive support of heat absorbing material such as soapstone, and a heater element secured thereto but spaced at a short distance therefrom, whereby the element first may be 25 raised to a high temperature upon the application of electric current, and useful heat immediately radiated therefrom; then heat gradually imparted to the heat absorbing body until its temperature is high 30 and it cooperates with and boosts the temperature of the heating element; and finally useful heat drawn gradually from the heat absorbing material after the electric energy is cut off.

Other objects and advantages of my invention will be set forth hereinafter, and in order that my invention may be thoroughly understood, I will proceed to describe the same in the following specification 40 and then point out the novel features thereof in appended claims.

Referring to the drawings: Figure 1 is a plan view of a heater embodying my invention. The same heater is shown in partial 45 sectional end and side elevations respectively in Figs. 2 and 3. Fig. 4 is a perspective view of one of the clips utilized to support the resistance conductor of the heater. Fig. 5 is a side elevation shown 50 partially in section of a heater structure embodying a pair of heaters of the character shown in Figs. 1, 2 and 3, together with a suitable frame and connections for uniting them into a unitary structure. A bottom

plan view of the same structure is shown in 55 Fig. 6.

With special reference to Figs. 1, 2 and 3, the heater here shown is complete in itself and may be used independently of the frame structure shown in the other 60 figures. It comprises a slab or plate 10 of soapstone or other electric insulating and heat absorbing material, having a plurality of transverse grooves 11, and a zigzag ribbon resistance conductor 12. 65

A pair of terminal studs 13—14 extend through the plate near its respective ends and adjacent to one of its sides as shown in Fig. 1. Each of the studs has a square or rectangular head 15 which fits into one 70 of the grooves 11. They are thus prevented from turning and at their ends they are provided with slots 16 into which the ends of a pair of resistance conductors are inserted. They are preferably braised or 75 soldered in place. The resistance conductors are supported in addition to the support furnished by the terminals 13 and 14, by a plurality of clips 18 which are similar to each other and are held in position by 80 screws 19, as clearly shown in Figs. 2 and 3. The holes through which the screws extend are preferably counterbored so that the heads are below the surface of the plate.

As shown in perspective in Fig. 4, each 85 of the clips 18 comprises a nut 20 having a slot 21 into which is set an L-shaped supporting bracket 22 preferably formed of sheet metal. The nut itself is also preferably formed of sheet metal of somewhat 90 heavier stock by folding a rectangular strip on itself. The outwardly extending arm of the bracket 22 is provided with a notch 23 and is folded inwardly with a tongue 24 extending laterally through the notch to 95 provide a double support for the resistance ribbon conductor. The holes through which the clamping screws 19 extend are preferably located substantially in the center of the grooves 11 in the plate 10, the zigzag 100 ribbon being mounted in sections directly over the grooves and the nuts 20 being shaped to fit into the grooves which prevent their turning.

The several rows of zigzag resistance ribbon may be interconnected in any suitable manner, for example, as shown in Fig. 1, they may be connected in two complete cir-

cuits terminating at the respective terminals 13—14.

On the back of the slab or plate 10 the terminal studs 13—14 extend outwardly and are provided with the usual clamping and terminal nuts 25 by which circuit conductors or bus-bars may be secured to and connected to the studs.

Referring to Figs. 5 and 6, more than one of the heaters of the preceding figures may be assembled into a unitary structure by means of a supporting frame 26 which is built up of angle strips 27 welded or otherwise connected at their corners, a central transverse strip 28 which is welded to the side bars and longitudinal bars 29 which are secured to the frame by bolts 30 which extend through suitable holes 31 in the soap-stone. The terminal studs of the respective heaters are interconnected by rigid connecting strips 35 and 36, the studs at the extremities of the complete structure being provided with suitable conducting strips 37—38 and 39 which terminate and extend slightly beyond one end of the structure and are insulated from and secured to the frame in any suitable manner.

The frame is sufficiently rigid to permit the structure to be handled as a unit and while I have shown the structure as consisting of two heaters any number may be united in a similar manner within the spirit and scope of my invention, and I intend that only such limitations be imposed as are indicated in the appended claims.

What I claim is:

1. A heater comprising a slab of heat ab-

sorbing material, a heating conductor supported by said slab and arranged substantially parallel to one of its surfaces, and means for spacing the heating conductor from the adjacent surface of the slab, whereby the heat transfer from the heating conductor to the slab is effected largely by radiation.

2. An electric heater comprising a solid body of heat absorbing material having a surface provided with a plurality of substantially parallel grooves, spaced supports secured to the body in said grooves and extending outwardly from the surface, and a heating conductor arranged close to but spaced from the surface of the body and mounted on said supports.

3. A heater comprising a slab of electric insulating and heat absorbing material having a plurality of substantially parallel grooves, angle supports mounted in said grooves and secured to the slab, and a zigzag resistance ribbon secured to said supports and mounted on edge relative to the surface of the slab, said ribbon being adjacent to but spaced slightly from the surface of the slab whereby the heat transfer from the resistance conductor to the slab is effected largely by radiation.

In testimony whereof I have hereunto set my hand in the presence of two subscribing witnesses, this 18 day of May, 1914.

WILLIAM S. HADAWAY, JR.
